UNITED STATES PATENT OFFICE.

EVERETT E. ROBINSON, OF GRUNDY CENTER, IOWA.

CLOTHES-LINE SUPPORT.

1,242,867.

Specification of Letters Patent.

Patented Oct. 9, 1917.

Application filed May 16, 1917. Serial No. 169,006.

To all whom it may concern:

Be it known that I, EVERETT E. ROBINSON, a citizen of the United States, residing at Grundy Center, in the county of Grundy 5 and State of Iowa, have invented new and useful Improvements in Clothes-Line Supports, of which the following is a specification.

This invention is a clothes line support 10 more particularly adapted for domestic use wherein the several component parts thereof are removable and detachable, and when not in use may be stored within doors where they may be fully protected from the elements.

It may also be employed as a support for a hammock.

The objects of the invention are to provide a support that will consist of few parts, 20 strong and rigid in construction and assembly, affording points between which may be stretched clothes lines, hammocks, or other weight carrying members, and one whose several parts may be removed from their 25 operative position for placing in storage.

The invention, broadly stated, comprises a standard, a permanent socket and a brace therefor, an adjustable hook in the upper end of the standard, which hook is adapted 30 to coöperate with a spreader member having side elements, a spacing element coöperating with one end of each of the side elements, weight carrying members connected to the spreader, and a brace connected to the 35 spacing element and slidably secured to the standard, said brace operating to prevent rotation of the spreader member when in one position, and when in other positions serves to rotate the spreader.

One practical form of construction and assembly will be described and illustrated in the accompanying drawing, in which:—

Figure 1 is a perspective view of one assembled support;

Fig. 2 is a side elevation of a support as utilized for swinging a hammock; and

Fig. 3 is an enlarged detail of the spreader member.

In the preferred embodiment shown, a 50 concrete foot 5 is provided with a socket that may also have a lining as indicated at 6, so as to prevent the chipping or enlarging of the socket hole. This concrete foot may be positioned in the ground at some

convenient point, and as this device is more 55 particularly adapted for domestic use, the foot and a companion foot will probably be placed in the back-yard of a dwelling at suitable points.

Adapted to be inserted within the socket 60 lining 6 is a standard 7, which is preferably formed of iron pipe or some material having a similar shape of sufficient strength and rigidity. The standard 7 may be of any suitable or convenient type that is efficient 65 for the purpose for which it is designed. To maintain the standard 7 in a vertical plane and also to assist in taking up strain, there is provided a brace which is provided with an angular end 8 carrying thereon suitable 70 threads 9. To coöperate with these threads there is employed a locking nut indicated by the nut and its handle 10.

The body portion 11 of the brace is connected to the angular portion 8 and terminates in a hook 12. This hook 12 coöperates with an eye 13 that is permanently embedded 75 in a concrete foot block 14, that is suitably spaced away from the concrete foot block 5.

Near the upper end of the standard 7, 80 there is provided a suitable aperture through which passes a hook bolt indicated at 15 having the threads 16 formed thereon. To coöperate with these threads there is a nut having a handle indicated at 17. The hook 85 part of this bolt is indicated at 18.

To coöperate with this hook 18, there is a spreader member, which has the side elements 19 and 20. The side element 19 is provided with an eye 21 at one end, and at 90 the other end with a similar eye indicated at 22. The side element 20 is provided with an eye 23, and at its other end there is a similar eye indicated at 24 and 23, respectively. To coöperate with the eyes 22 and 24 and 23, 95 respectively there is a spacing element indicated at 25. The ends of this spacing element may be of suitable form so as to maintain the side elements 19 and 20 through the eyes 22 and 23 in a suitable spaced relation. 100

Adjustably mounted upon the standard 7 is a collar 26 that is provided with suitable means to clamp it or retain it in any position upon the standard and is also provided with a suitable connection 27 where the 105 brace 28 is connected thereto. The other end of this brace 28 may be provided with an eye indicated at 29 to coöperate with the spacing

element 25. The brace 28 by means of its collar 26 may be moved to several positions that is the up and down movement of the collar 26 will tend to rotate the spreader member through its spacing element 25.

By means of the clamping portion 30, of the collar 26, the spreader element may be secured in any one of several positions.

The clothes lines are indicated at 31, 32, 10 and 33. The line 31 is connected to the eye 22. The line 32 is connected to the eye 28 and the line 33 is connected to the hook 18 of the hook bolt 15.

In order to use this support as a hammock support, the spreader member with its brace and collar are removed from engagement with the standard and the hook 18. Then the eye formed on and carried by the hammock may be attached to the hook 18, and by 20 means of the handled nut 17 the hammock may be adjusted in several positions, and also be securely held. The handled nut 17 operating on the threads 16 formed on the eye-bolt 15 serves to position the hammock 25 in several horizontal planes.

The movement of the handled nut 17 upon the threads by utilizing the spreader member serves to loosen or tighten the several clothes lines.

30 Secured to the standard 7 is a suitable receptacle which may be made of galvanized iron to provide a water and dust-proof clothes pin box. The body of the box or receptacle is indicated at 34, and the lid therefor at 35. The lid 35 is preferably hinged to the receptacle portion at the rear end adjacent the standard 7, the hinges being indicated at 36.

In order to maintain the lid 35 in a raised 40 position, the arm 37 may be employed which is of the usual type of construction employing elongated slot coöperating with a pin. The arm 37 may be hingedly connected to the top 35 in the usual manner. The top 35 is also provided with downwardly directed 45 flanges, indicated at 38, which serve as drip edges to prevent moisture from entering into the receptacle 34.

The receptacle 34 may be provided with 50 any usual type of connection so that it may be adjustably secured to the standard 7. One type of connection shown is that of a

hinged collar, including a thumb screw, the assembly of which is indicated at 39.

Minor changes in the form, proportions, 55 and details of construction may be resorted to, without departing from the spirit of the invention or the scope of the appended claims.

What is claimed as new is:—

1. In a device of the character described, the combination with a standard and socket therefor and a brace for said standard, a removable and foldable spreader member for the clothes line, means adjustable longitudinally for connecting the spreader to the standard, and adjustable retaining means interposed between the standard and the spreader member. 65

2. In a device of the character described, 70 the combination with a standard and socket therefor, of a foldable and removable spreader member having its elements loosely connected together, means adjustable longitudinally for connecting the spreader to the 75 standard, and a brace slidably secured to the standard and the spreader member so that the said spreader may be partially rotated by the movements of the latter brace and retained in a plurality of positions. 80

3. A device of the character described comprising a standard, a spreader member adjustably and removably secured to the standard and having side elements provided with eye ends, and a spacing element connected with one eye of each of the side elements, and a brace slidably on the standard including engaging and retaining means for the standard, said brace being connected with the spacing element, one of the side elements coöperating with the brace and serving to place and retain the spreader in a variety of positions. 85

4. The combination with a standard and a brace therefor, of a spreader member consisting of a spacing element and side elements, which elements are loosely connected with each other, an adjustable connection between the standard and the spreader, and means slidably secured to the standard and 95 connected with the spreader serving to retain the spreader in a variety of positions. 100

In testimony whereof I affix my signature.

EVERETT E. ROBINSON.
